WELL DEVICE

James M. Clark, Carthage, Tex.

Application June 22, 1946, Serial No. 678,655

7 Claims. (Cl. 166—12)

1

This invention relates to new and useful improvements in well devices.

One object of the invention is to provide an improved locking mechanism which is particularly adaptable for use with well packers, although it may be used with other well devices which are designed to be lowered into a well bore and locked in place therein.

An important object of the invention is to provide a well device having an improved locking mechanism including locking elements expansible to locking position upon rotation of an actuating mechanism, and wherein said actuating mechanism also effects distortion of a sealing element into sealing position; the well device being readily removable from locked sealing position by upward movement of the well flow conductor to which it is attached, whereby removal of the device from the well bore may be accomplished without the necessity of rotation of any of the parts.

A further object of the invention is to provide an improved well device of the character described which is particularly adaptable for use as a well packer and having sealing means which is held in sealing position by mechanical distorting means, whereby the device provides for effective seal against pressures from above or below the device.

A particular object of the invention is to provide a well device, of the character described, having anchoring means and sealing means arranged to be actuated to anchoring position and to sealing position by rotation of the well flow conductor to which the device is connected, actuation of the anchoring and sealing means being effected by threaded members, one of which is expansible or retractable from threaded engagement with the other, whereby the threaded engagement normally holding the anchoring means and sealing means in expanded anchoring and sealing position may be released to permit retraction of such anchoring and sealing means from expanded position, and the well device may be removed from the well, upon an upward pull of the well flow conductor to which it is attached.

Additional objects and advantages of the invention will readily be apparent from a reading of the following description of a device constructed in accordance with the invention, and reference to the accompanying drawings, wherein:

Figure 1 is a view, partly in elevation and partly in section, of the upper portion of a well device constructed in accordance with the in-

2

vention, and showing the same in position for lowering into a well bore.

Figure 2 is a continuation of Figure 1, showing the lower portion of the device.

Figure 3 is a view, partly in elevation and partly in section, of the upper portion of the device, showing the same in locked position in the well bore.

Figure 4 is a continuation of Figure 3, showing the lower portion of the device in locked position.

Figure 5 is a view, partly in elevation and partly in section, of the upper portion of the device, showing the same in retracted or removing position.

Figure 6 is a continuation of Figure 5, showing the lower portion of the device in retracted position.

Figures 7 through 9 are horizontal cross-sectional views taken on the lines 7—7, 8—8, and 9—9 of Figure 1.

Figure 10 is a horizontal cross-sectional view taken on the line 10—10 of Figure 3, and

Figure 11 is a horizontal cross-sectional view taken on the line 11—11 of Figure 5.

In the drawings, the numeral 15 designates an elongate tubular mandrel having an axial bore 16 extending therethrough. The lower end of the mandrel is provided with an external annular flange or collar 17 which is illustrated as being threaded onto the mandrel but may be affixed thereto by welding or otherwise. The bore of the collar is provided with screw threads whereby a well flow conductor or tubing T may be connected to the lower end of the mandrel.

Gripping elements or slips 18 having serrations or gripping teeth 18a formed on their outer surface are connected to the collar 17 by means of elongate spring handles 19 which are bolted at their lower ends to the collar and are bowed outwardly at their mid-portion to engage the wall of a well bore or well casing C for purposes which will be hereinafter explained. The upper ends of the spring handles 19 extend through openings 20 formed in an external annular flange 21 secured to the mandrel 15 above the collar 17, whereby the upper portions of the spring handles are supported against rotation about the mandrel but may move radially with respect thereto.

A slip expander or wedge member 22 having an upwardly flared frusto-conical external surface 23 thereon is slidable on the mandrel above the flange 21 and is adapted to engage between the slips 18 to force said slips outwardly into grip-

ping engagement with the wall of the well casing C. An elongate cylindrical sleeve 24 is connected to the upper end of the expander member 22 and is slidable therewith on the mandrel. An elongate flexible packing sleeve or element 25, made of fabric-reinforced rubber, "neoprene," or other suitable material, surrounds the expander sleeve 24 and has its lower end reduced and confined within an annular groove 26 formed in the upper end of the expander member. The upper end of the packing sleeve is also reduced slightly in diameter and is tightly engaged by an annular thimble 27 which is slidable on the expander sleeve and is confined thereon by means of a retaining collar 28 which is threaded onto the upper end of said expander sleeve.

The lower end of the bore of the expander member 22 is enlarged to provide a packing recess 30 in which a packing member 31, preferably a plurality of inverted V-shaped packing rings, is confined by means of a gland nut 32 threaded into the recess. Obviously, the packing rings may be arranged to face both upwardly and downwardly to seal against pressures from both above and below to prevent flow of fluid in either direction between the exterior of the mandrel and the bore of the expander member.

Above the upper end of the expander sleeve 24, the mandrel is provided with an external annular enlargement 33 which is formed with external screw threads 34, preferably coarse Acme or coarse round threads. For ease of manufacture and assembly, the mandrel is formed in two sections which are joined by screw threads, preferably at this enlarged section 33 as clearly shown in Figures 1 and 3.

An actuating member or cylinder 35, having at its mid-portion a short section of internal screw threads 36 corresponding to the external threads 34 on the mandrel, telescopes the upper end of the mandrel and is adapted to have its internal threads mesh with the external threads on the mandrel. An internal annular flange 37 is formed at the lower end of the cylinder and this flange is slidably confined on the expander sleeve 24 between the retaining nut 28 and the thimble 27, for purposes which will hereinafter be explained.

The cylinder is provided with a plurality of longitudinally extending slots 38 spaced equidistant around the periphery thereof and extending from a point slightly above the internal flange 37 to the upper end of the cylinder, whereby the cylinder is divided into a plurality of sections 39 which are normally resiliently spread outwardly at their upper ends, as shown in Figure 5.

The upper end of the actuating cylinder is provided with an annular external flange 40 forming a downwardly facing annular shoulder 41 therebeneath. The upper portion of the flange 40 is substantially frusto-conical in shape to form tapered surfaces 42 on the upper outer ends of the sections 39 which are adapted to ride upon correspondingly tapered surfaces 43 formed in the bore of a bell member 44 which telescopes the upper end of the mandrel and the upper end of the actuating cylinder. The bell member 44 has an internal annular flange 45 at its lower end providing an upwardly facing shoulder 46 which is adapted to be engaged by the downwardly facing shoulders 41 on the actuating cylinder sections 39 when said sections are spread apart in the manner illustrated in Figure 5. A plurality of radially inwardly extending longitudinal ribs 47 are provided in the

bore of the bell member and are adapted to engage within the slots 38 formed in the actuating cylinder, whereby rotation of the bell member imparts rotation to the actuating cylinder. An abutment or stop ring 48 is mounted within the upper end of the bell member and the lower surface of the ring is adapted to be engaged by the upper end of the actuating cylinder to limit upward movement of the cylinder within the bell member.

The upper end of the bell member is reduced and provided with internal screw threads and a tubular adapter member or sub 50 is connected thereto. The upper end of the bore of the sub 50 is also reduced and is provided with internal screw threads which are arranged to be connected to the lower end of a well flow conductor or tubing T, whereby the device may be lowered into the well bore by means of such well flow conductor.

A plurality of inwardly extending lugs 49 are provided in the reduced bore of the bell member above the ring 48, and the upper end of the mandrel 15 is adapted to slide between these lugs. A ring of packing 51 is mounted on the upper end of the mandrel between a retaining nut 52 and a stop ring or nut 53 which are screw-threaded onto the upper end of the mandrel. The diameters of the retaining nut and the stop nut are slightly less than the bore of the sub 50 whereby they are slidable therein, and the packing ring is arranged to seal between the bore wall of the sub and the exterior of the mandrel to prevent fluid leakage therebetween in either direction. This packing arrangement is retained within the bore of the sub and is slidable therein between the lugs 49 at the upper end of the bell member and the reduced upper end of the bore of the sub.

It will be seen, therefore, that the mandrel is slidably connected with the tubing string or flow conductor T and that the assembly may be suspended from such well flow conductor.

In use, the well flow conductor or tubing T is connected to the lower end of the collar 17 and to the upper end of the sub 50, as clearly illustrated in Figures 1 and 2, and the device is then lowered into the well casing C by means of such tubing. During the lowering operation, the parts of the device assume the position illustrated in Figures 1 and 2, wherein the bell member 44 is moved downwardly with respect to the actuating cylinder 35 until the upper ends of the sections 39 engage the stop ring 48. In this position, the short section of internal screw threads 36 at the mid-portion of the cylinder is positioned above and out of mesh with the external threads 34 on the enlarged portion 33 of the mandrel. It will be seen, therefore, that as the tubing is lowered the stop ring 48 acts upon the upper end of the cylinder 35 to move the same downwardly, and, since the internal screw threads of the cylinder 35 are out of mesh with and above the external screw threads of the enlarged section 33 of the mandrel, it is apparent that the lower end of the internal screw threads of the cylinder will engage the upper end of the external screw threads of the mandrel to impart downward movement to the mandrel.

The internal annular flange at the lower end of the actuating cylinder 35 is engaged under the retaining collar 28 at the upper end of the expander member sleeve 24, whereby the expander member and the packing sleeve 25 carried thereby are supported by such flange and are thus so positioned that the slips 18 are located adjacent the

reduced lower end of the expander member 22, whereby the slips are retracted and in non-gripping position and the device may readily be lowered into the well casing.

When the depth in the well bore at which it is desired to set the well device has been reached, the upper portion of the well flow conductor or tubing T is rotated in a clockwise direction to impart rotation to the bell member 44. Rotation of the bell member is transmitted by means of the ribs 41 to the actuating cylinder 35 to cause its internal screw thread section 36 to mesh with the external screw threads 34 on the mandrel. The mandrel is restrained against rotation by the frictional engagement of the bowed mid-portions of the spring arms 19, which are connected to the collar 17 at the lower end of said mandrel, with the inner wall of the well casing C. Therefore, rotation of the tubing T will cause the bell member to rotate the actuating cylinder 35, while the mandrel 15 is restrained against rotation by the frictional engagement of the spring arms with the casing.

Upon continued rotation, the meshing of the threads 36 on the cylinder with the threads 34 on the mandrel causes the cylinder to move downwardly with respect to the mandrel. This downward movement of the cylinder causes its lower end to engage the thimble 27 at the upper end of the packing sleeve 25 and to move the packing sleeve and the expander member 22 downwardly relative to the mandrel, whereby the frusto-conical section 23 of the expander member is moved downwardly between the slips 18 to force the same outwardly into gripping engagement with the casing.

When the expander member has forced the gripping slips 18 into tight gripping engagement with the casing C, the expander member is held stationary and continued downward movement of the actuating cylinder 35 forces the thimble 27 downwardly toward the expander member 22 to distort the packing sleeve 25 therebetween into sealing engagement with the wall of the casing, as clearly shown in Figures 3 and 4. Rotation of the well tubing is continued until a tight gripping engagement of the slips 18 with the casing is obtained and the packing sleeve 25 is distorted into a positive sealing engagement with the casing.

The parts of the device have, at this time, assumed the position illustrated in Figures 3 and 4 and the packer is set in anchored sealing position in the well casing. Well fluids from below the packer will enter the well tubing T therebelow and flow therethrough, through the mandrel 15, the sub 50 and the tubing T above the packer to the surface of the well. The well fluid cannot by-pass the packer because of the provision of the packing gland 31 at the lower end of the expander member. Fluid pressure above the packer cannot enter the packer mandrel because of the sealing engagement of the ring 51 with the exterior of the mandrel and the interior of the sub 50.

It will be seen, therefore, that the locking elements and packing sleeve are expanded into anchored sealing position by the mechanical actuation of the actuating cylinder 35 which is screw threaded onto the enlargement 33 formed on the mandrel, and are positively and mechanically held in such anchored sealing position independently of the weight of the well tubing to provide an effective seal against pressures from above or below the device.

When it is desired to remove the packer from the well bore, it is only necessary to lift the well flow conductor or tubing T. Such upward movement of the tubing raises the bell member 44 to move the tapered surfaces 43 upwardly with respect to the upper ends of the sections 39 of the actuating cylinder, whereby said sections are permitted to resiliently spread outwardly at their upper ends in the manner illustrated in Figure 5. In such position the shoulder 41 below the flange 40 on the upper end of the cylinder engages and is supported upon the upwardly facing shoulder 46 at the lower end of the bell member and the sections are spread sufficiently wide apart at their upper ends to completely free the internal screw thread section 36 from meshing engagement or interference with the external threads 34 on the mandrel. Continued upward movement of the bell member is transmitted, through the engagement of the shoulders 41 and 46, to the internal flange 37 at the lower end of the actuating cylinder to cause the same to engage the under side of the retaining collar 28 at the upper end of the expander sleeve 24 to lift said sleeve and thus lift the expander member 22 carried thereby upwardly from between the gripping slips 18. The gripping slips are restrained against movement by the frictional engagement of the bowed spring arms 19 with the casing, whereby the packing sleeve and the expander member 22 may be moved upwardly with respect to said slips to permit retraction of the packing sleeve and the slips. The engagement of the bowed spring arms with the casing also prevents upward movement of the mandrel 15. Since the upper ends of the sections 39 of the actuating cylinder are permitted to spread outwardly a sufficient distance to completely free the internal screw thread section 36 from meshing engagement with the external screw threads 34 on the mandrel, the actuating cylinder may be moved upwardly with respect to the mandrel or, conversely, the mandrel may in effect move downwardly with respect to the actuating cylinder and the parts carried thereby, to permit the slips 18 to move to retracted non-gripping position.

The mandrel will continue to remain substantially stationary until the stop ring or nut 53 at the upper end thereof is engaged by the inwardly facing lugs 49 at the upper end of the bore of the bell member. Continued upward movement of the well tubing will then lift the entire device from within the well casing, with the parts in the position shown in Figures 5 and 6.

Should it be desired to reset the packer, the well tubing may be again lowered to move the bell member downwardly and cause the tapered surfaces 43 to engage the tapered upper ends 42 of the resilient sections 39 of the actuating cylinder to press the upper ends of such sections inwardly to the position illustrated in Figure 1, whereupon the cylinder may again be rotated to expand the slips and packing sleeve into anchoring and sealing position in the manner already described. Or, if desired, the packer may be first moved further upwardly or downwardly within the well to a new position and then anchored.

From the foregoing, it will be seen that a well device has been provided having locking elements 70 which are expandible to locking position upon rotation of an actuating mechanism and wherein the locking elements are held in such locking or anchoring position mechanically by said actuating mechanism, and independently of the weight of the well flow conductor, until it is de-

sired to remove the device from within the well bore; the device being readily removable from locked position by upward movement of the well flow conductor to which it is connected, whereby removal is effected without the necessity of rotation of any of the parts in either direction. Thus, the mechanical difficulties normally attendant upon locking mechanisms expanded into locking position by rotation of the well tubing are eliminated, since it is not necessary to rotate the tubing in a counter-clockwise direction with the resulting possibility of disconnecting sections of the tubing above the device without actually releasing the device from anchored position.

It will also be seen that the well device is particularly adaptable for use as a well packer, and that the actuating mechanism which is utilized for expanding the locking elements to anchoring position may also be utilized for positively distorting and maintaining the packing element in such distorted sealing position independently of the weight of the well flow conductor, whereby an effective seal is provided against pressures from either above or below the device; the packer being removable from the well bore upon upward movement of the well flow conductor to which it is connected without the necessity of rotation of the conductor or any parts of the device.

Also, the device may be released from anchoring position and moved to a new elevation in the well bore, either above or below the original position, and reanchored therein.

It will also readily be seen that, while the device has been illustrated and described as including the improved locking mechanism in combination with a well packing sleeve, the locking mechanism may very well be used with other well devices which are designed to be lowered into a well bore and locked in place therein, such as cementing plugs, cementing squeeze plugs, liners, and the like.

The foregoing description of the invention is explanatory only, and changes in the details of the construction illustrated may be made by those skilled in the art, within the scope of the appended claims, without departing from the spirit of the invention.

What I claim and desire to secure by Letters Patent is:

1. In a well device, the combination including, an elongate tubular mandrel having an external screw threaded section, expandible gripping means carried by the mandrel, expander means slideable on the mandrel and adapted to engage the gripping means to move said gripping means to gripping position upon longitudinal movement of the expander means in one direction relative to the mandrel, actuating means for the expander means movable on the mandrel and having an internal screw thread adapted to engage with the thread on said mandrel, said actuating means being divided whereby it may be opened to a non-engaging position with respect to the external thread on the mandrel, and means for normally maintaining the actuating means in position for the internal thread thereof to engage and mesh with the thread on the mandrel.

2. In a well device, the combination including, an elongate tubular mandrel having an external screw threaded section, expandible gripping means carried by the mandrel, expander means slideable on the mandrel and adapted to engage the gripping means to move said gripping means to gripping position upon longitudinal movement of the expander means in one direction relative

to the mandrel, actuating means for the expander means movable on the mandrel and having an internal screw thread adapted to engage with the thread on said mandrel, said actuating means being divided whereby it may be opened to a non-engaging position with respect to the external thread on the mandrel, means for normally maintaining the actuating means in position for the internal thread thereof to engage and mesh with the thread on the mandrel, and means carried by said maintaining means and engaging the actuating means for imparting rotation from the said maintaining means to the actuating means to move the same into engagement with the expander means to move said expander means for expanding said gripping means to gripping position, said maintaining means being movable with respect to the actuating means to permit the actuating means to open, and means urging said actuating means to open position to disengage the thread therein from the thread on the mandrel to permit the expander means to move in the opposite direction from engagement with the gripping means to permit retraction of the gripping means from gripping position.

3. In a well device, the combination including an elongate tubular mandrel having an external screw threaded section, expandible gripping means carried by the mandrel, expander means slideable on the mandrel and adapted to engage the gripping means to move said gripping means to gripping position upon longitudinal movement of the expander means in one direction relative to the mandrel, actuating means for the expander means movable on the mandrel and having an internal screw threaded section adapted to engage with the threads on said mandrel, said actuating means being slotted from one end through said threaded section and resiliently spread outwardly whereby said threaded section is urged to spread apart to a non-engaging position with respect to the external thread on the mandrel, and means for normally maintaining the actuating means in position for the internal thread thereof to engage and mesh with the thread on the mandrel.

4. In a well device, the combination including, an elongate tubular mandrel having an external screw threaded section, expandible gripping means carried by the mandrel, expander means slideable on the mandrel and adapted to engage the gripping means to move said gripping means to gripping position upon longitudinal movement of the expander means in one direction relative to the mandrel, actuating means for the expander means movable on the mandrel and having an internal screw thread adapted to engage with the thread on the mandrel, said actuating means being divided whereby it may be opened to a non-engaging position with respect to the external thread on the mandrel, and means for normally maintaining the actuating means in position for the internal thread thereof to engage and mesh with the thread on the mandrel, said maintaining means being movable with respect to the actuating means to permit the actuating means to open, and means for opening said actuating means to disengage the thread therein from the thread on the mandrel to permit the expander means to move in the opposite direction from engagement with the gripping means to permit retraction of the gripping means from gripping position.

5. In a well device, the combination including, an elongate tubular mandrel having an external

screw threaded section, expandible gripping means carried by the mandrel, expander means slideable on the mandrel and adapted to engage the gripping means to move said gripping means to gripping position upon longitudinal movement of the expander means in one direction relative to the mandrel, actuating means for the expander means movable on the mandrel and having an internal screw thread adapted to engage with the thread on said mandrel, said actuating means being divided whereby it may be opened to a non-engaging position with respect to the external thread on the mandrel, means for normally maintaining the actuating means in position for the internal thread thereof to engage and mesh with the thread on the mandrel, and means for imparting rotation to the actuating means to move the same into engagement with the expander means to move said expander means for expanding said gripping means to gripping position, said maintaining means being movable with respect to the actuating means to permit the actuating means to open, and means for opening said actuating means to disengage the thread therein from the thread on the mandrel to permit the expander means to move in the opposite direction from engagement with the gripping means to permit retraction of the gripping means from gripping position.

6. A well device including, an elongate tubular mandrel having an external screw threaded section, expandible gripping means carried by the mandrel, expander means slideable on the mandrel and adapted to engage the gripping means to move said gripping means to gripping position upon longitudinal movement of the expander means in one direction relative to the mandrel, actuating means for the expander means movable on the mandrel and having an internal screw threaded section adapted to engage with the threads on said mandrel, said actuating means being slotted from one end through said threaded section and resiliently spread outwardly whereby said threaded section is urged to spread apart to a non-engaging position with respect to the external thread on the mandrel, a bell member engaging over the slotted section of said actuating means for normally maintaining the slotted, threaded section of the actuating means in position to engage and mesh with the thread on the mandrel, and means carried by the bell member and engaging the actuating means for imparting rotation from the bell member to the actuating means to move the same into engagement with the expander means to move said expander means for expanding said gripping means to gripping position, said bell member being movable with respect to the actuating means to permit said slotted section thereof to spread apart to disengage the thread therein from the thread on the mandrel to permit the expander means to move in the opposite direction from engagement with the gripping means to permit retraction of the gripping means from gripping position.

7. A well device including, an elongate tubular mandrel having an enlarged external screw threaded section near its mid-portion, a sleeve telescoping the upper end of the mandrel and forming a lost-motion connecting means for connecting the mandrel with a well flow conductor, expandible gripping means carried by the mandrel, an expander member slideable on the mandrel below the enlarged portion and above the gripping means and having a wedge surface adapted to engage the gripping means to move said gripping means to gripping position upon longitudinal movement of the expander in one direction relative to the mandrel, an actuating cylinder movable on the mandrel and having an internal screw threaded section adapted to engage with the threads on the enlarged portion of the mandrel, said cylinder being provided with a plurality of longitudinal slots extending throughout the major portion thereof so as to permit the section of the upper end of the cylinder defined by said longitudinal slots to spread apart whereby the internal threaded section is moved to non-interfering non-engaging position with respect to the external threads on the mandrel, a bell member carried by the lost-motion connecting sleeve and engaging over the spreadable sections of the actuating cylinder for normally maintaining said spreadable sections of the upper portion of the actuating cylinder in retracted unexpanded position for the internal threaded section to engage and mesh with the threads on the mandrel, and means carried by the bell member and engaging the actuating cylinder for imparting rotation from the bell member to the cylinder to move the same downwardly into engagement with the expander member to move said expander member with respect to the gripping means to expanding said gripping means to gripping position, said bell member being movable upwardly with respect to the cylinder to permit the spreadable longitudinal sections of the upper portion of the cylinder to spread to disengage the threaded section therein from the threads on the mandrel to permit the expander member to move in the opposite direction from engagement with the gripping means to permit retraction of the gripping means from gripping position.
